[57] CLAIM

The ornamental design for a combined bottle and cup, as shown.

DESCRIPTION

FIG. 1 is a top plan view of a combined bottle and cup showing my new design;

FIG. 2 is an elevational view;

FIG. 3 is a bottom plan view; and

FIG. 4 is an elevational view showing another embodiment of my new design wherein the only change is in the embossed band around the cup.

FIG. 1.

FIG. 2.

FIG. 3.

FIG. 4.
